Patented May 22, 1917.

UNITED STATES PATENT OFFICE.

ALBERT W. COCHRAN AND FRED M. YOUNGS, OF PORTLAND, OREGON.

MAKE-READY OF IMPRESSION-CYLINDERS OF PRINTING-PRESSES.

1,227,557.

Specification of Letters Patent.

Patented May 22, 1917.

Application filed August 7, 1916. Serial No. 113,676.

To all whom it may concern:

Be it known that we, ALBERT W. COCHRAN and FRED M. YOUNGS, citizens of the United States, and residents, respectively, of the city of Portland, county of Multnomah, State of Oregon, have invented a certain new and useful Improvement in Make-Ready of Impression-Cylinders of Printing-Presses, of which the following is a specification.

Our invention particularly relates to newspaper presses and has for its object the providing of impression cylinders with a "make ready" or circumferential covering which will produce clear-cut imprints, and which, furthermore, is economical with regard to its cost, application and length of service.

In order to understand the nature of our invention, it is convenient to state, in the first place, the undesirable conditions now met with in the art, and contrasting therewith the beneficial results obtained from our improvement. In so doing reference will be had to the accompanying drawings, in which:

Figure 1 shows diagrammatically an enlarged perspective elevation of the capital letter I in block type;

Fig. 2 shows a cross-section of such type, and a partial, longitudinal section of the impression cylinder provided with an imperfect "make ready," and this figure represents in exaggerated form the undesirable printing action likely to result;

Fig. 2^a shows diagrammatically the blurred imprint produced by said improper condition;

Fig. 3 shows a diagrammatic, partial perspective, partly in section, of an impression cylinder having our improved "make ready" or circumferential covering applied thereto;

Fig. 4 shows a manner of preparing our improved "make ready" for being fastened on the circumference of the cylinder;

Fig. 5 is an exaggerated cross-section of our said "make ready";

Fig. 6 illustrates diagrammatically, and comparatively to Fig. 2, the improved results in the printing operation obtained by our invention; and

Fig. 6^a represents a clear-cut imprint, to obtain which is the purpose of our invention.

In cylinder printing presses the impres-

sion cylinder must be "made ready," and to this end is circumferentially covered with a resilient material adapted to provide a surface facilitating the printing operation of the companion printing cylinder; referring, by the latter term, to the cylinder which carries the stereotype plate.

The two cylinders must have the same relative working diameter, in order to run at the same speed, for if they run at unequal speed there would be a tendency to drag the plate, relatively, over the paper supported by the impression cylinder, and so blur the imprint.

The "make ready" of the impression cylinder, as heretofore practised, consisted in covering its circumference with a rubber blanket and then covering the latter with a felt blanket. The difficulty experienced in such "make ready" is, the felt blanket permits considerable "sinking in," which must be guessed at, because allowance must be made in adjusting the working diameters of the two cylinders; referring to those diameters which the cylinders respectively assume when the one carries the plate and the other the "make ready." The necessity for figuring out approximately the allowance to be made for the "sinking in" during the printing operation is shown, for instance, in newspaper work, where half tones are printed alongside of type. In such case, since the half tones require a heavier impression than the type, they must frequently be sacrificed in order to have a sufficiently light impression which will not blur the type by sinking it too deeply into the surface of the impression cylinder. The effect of having to sacrifice the half tones is readily seen in a careful scrutiny of newspaper prints in presses using the old mode of "make ready." The blur of the imprint of the type is due to the surface covering of the impression cylinder permitting the type to sink in so deeply as to cause the paper printed to be pressed against the side faces of the type, thus causing a distorted, instead of a true, clear-cut impression.

This undesirable effect may be graphically illustrated by the aid of the diagrammatic Figs. 1, 2, 2^a in the accompanying drawings. Fig. 1 represents a diagrammatic perspective of a type printing the capital letter I. Fig. 2 is a cross-section illustrating a likely undesirable contact of the sheet imprinted with the side faces of the type, due

100

110

to the fact that the "make ready" permits the type to sink too deeply into the surface. In other words, under such conditions, the surface portions d, d' of the "make ready" bring the paper imprinted in contact with the vertical edges b' of the type, thereby producing a blurred impression, as illustrated in Fig. 2^a, instead of a clear-cut imprint of the character, as illustrated by Fig. 6^a. These undesirable conditions are present where a rubber sheet or felt blanket, or both, are used. Furthermore, having reference to the undesirable conditions resulting when the two cylinders are of unequal relative working diameter, the unequal speed so resulting would have a tendency to pull the paper so hard as to cause it to tear; and in that case the torn end of the paper would have a tendency to wind up on the impression cylinder so tightly as to kill the resiliency of the felt blanket and render it unfit for further service, because felt possesses only a limited "come back" property, for its texture is susceptible of being matted down by sustained pressure; and in consequence of this inherent weakness in felt the blanket usually employed as a part of the "make ready" loses its "come back" even in ordinary work in a comparatively short period. Then there is this further disadvantage in the old style of "make ready:" The felt blanket will stretch, and has to be retightened from time to time, and in this way it is finally stretched so thin as to lose its resiliency. At the same time the diameter of the impression cylinder would be varied to such extend as to require it to be built up anew, in order to make its working diameter approximately equal to that of the printing cylinder, and prevent the consequences due to the working diameters of the two cylinders being unequal.

In seeking a remedy for said undesirable effects we have discovered an improved "make ready" for the impression cylinder, which provides the latter with a suitable covering sufficiently resilient to allow for the irregularities in the printing faces of the stereotype plate, at the same time resisting the forming of any hollows into which the printing character may sink, and cause the undesirable consequences illustrated by Figs 2, 2^a.

The "make ready" invented by us consists of a base h made of textile fabric coated with a thin layer of composition 1, consisting of ground cork and oxidized linseed oil. In making up this composition the linseed oil is dried and ground up, then the two articles are mixed, and then the mass is heated, and while still hot the composition is spread in the form of a layer on the textile base, and then rolled to the required uniform thickness, approximately .145 of an inch. This is the usual thickness of a built-up "make

ready," and it is to be noted that our "make ready" is to be used by itself, without any additional strips, felt blanket or rubber sheet, as heretofore required. Both and either of which possesses undesirable properties from which we get away by our invention, as mentioned. In other words, our new result can only be obtained by printing directly upon the surface of our "make ready," the intervening draw sheet not being considered as it merely serves to keep our "make ready" in place on the cylinder, and to keep the surface thereof clean. And it is required that our "make ready" have a substantial thickness in order to obtain the resiliency required.

The "make ready" is applied to the impression cylinder (as shown in Fig. 3) by bending the end h as illustrated in Fig. 4; such bent end being provided with holes f so as to adapt it to be secured on the hooks g provided for that purpose on the channel i of the impression cylinder.

In Fig. 3, i represents the impression cylinder, j the "make ready" or covering as a whole. The impression cylinder is provided with the usual reels m, m' , on the former of which one end of the draw sheet n is fastened, the other end being fastened on the reel m' . The draw-sheet encircling the "make ready" is covered, the latter being flexed around the cylinder, and by then winding up the reels m, m' , or one thereof, the draw-sheet is drawn tautly, and in so doing firmly holds the "make ready" on the circumferential surface of the impression cylinder.

Ground cork is especially adapted for making our "make ready" since it has the required resiliency for yielding to irregularities in the printing faces, and a "make ready" made as herein described has, furthermore, the stable "come back" required to maintain the impression surface in a uniform plane and also to resist the forming of cavities therein, for while resilient it is not so yielding as to permit crushing in, as does felt or rubber. Our improved "make ready" is particularly adapted for stereotype plates, which cannot be cast accurately, but present a more or less irregular printing face.

The effect obtained by my improved "make ready" is graphically illustrated in Figs. 6, 6^a. Assuming the capital letter I is being printed, the "make ready" j will yield sufficiently to allow for irregularities and produce a clear-cut imprint, such as is illustrated by Fig. 6^a, in comparison with Fig. 2^a; for the type cannot sink into the surface of the "make ready" to such extent as to cause the portions j' of the "make ready" to bring the sheet imprinted into contact with the vertical edges b' , and thus prevents blurs as e, e in Fig. 2^a.

Our invention also produces a cheaper "make ready," for the felt blanket must be made throughout of a good quality of wool, in order that it will have the necessary resiliency or come-back. And our invention has the further advantage that it requires less adjustment. In practice, with the old style of "make ready," after the press had been run for a time it necessitated readjustment of the "make ready." On the other hand, when our "make ready" is used, and has been adjusted after a day's run, it will stand up indefinitely without further adjustment. In trials heretofore made by us, our improved "make ready" has been used for six million impressions and is still in good condition, while the old style of "make ready," using a felt blanket, would be about used up in such work, and require renewal. Our "make ready" is to be used in place of both the rubber blanket and the felt blanket now in use.

We claim:

1. A "make ready" for impression cylinders consisting of a strip of substantial thickness made wholly of comminuted material having resilient properties similar to cork, held in mass by a suitable binding agent, and including other material adapted to hold the mass against pulling apart, said "make ready" being made of a thickness adapted for imprinting directly thereon.
2. A "make ready" for impression cylin-

ders consisting of a strip of substantial thickness made wholly of comminuted material having resilient properties similar to cork, held in mass by a suitable binding agent, and mounted on a base strip adapted to hold the mass against pulling apart, said "make ready" being made of a thickness adapted for imprinting directly thereon.

3. A "make ready" for impression cylinders consisting of a strip of substantial thickness made wholly of comminuted cork held in mass by a suitable binding agent, and mounted on a base strip adapted to hold the mass against pulling apart, said "make ready" being made of a thickness for imprinting directly thereon.

4. The combination with an impression cylinder, of a "make ready" consisting of a circumferential coating of substantial thickness made wholly of comminuted cork and held in mass by a suitable binding agent.

5. The combination with an impression cylinder, of a "make ready" consisting of a strip of substantial thickness made wholly of comminuted cork held in mass by a suitable binding agent and mounted on a base strip adapted to hold the mass against pulling apart, and a draw sheet holding said strip flexed about the cylinder, said "make ready" being made of a thickness adapted for impressing directly thereon.

ALBERT W. COCHRAN.

FRED M. YOUNGS.
